MEANS FOR PROTECTING MECHANISMS

Edward C. Ekstromer, Los Gatos, Calif., assignor
of one-half to Homer J. Lloyd, Los Gatos,
Calif.

Application November 20, 1934, Serial No. 753,989

9 Claims. (Cl. 286—27)

This invention relates to means for protecting mechanisms by removing liquids from locations wherein the liquids, if uncontrolled, would subsequently come into contact with the mechanisms and either damage or destroy the latter, and the invention is more particularly in the nature of an improvement upon the forms and arrangements of parts disclosed in my co-pending applications serially numbered 745,161 and 10 745,162, filed September 22, 1934.

As in the devices disclosed in my aforeslated applications, the present invention makes use of a reciprocally mounted receptacle carried by the mechanism to be protected for collecting liquid 15 and preventing same from reaching the mechanism, and an object of the present improvement is to better insure rapid and better and more positive displacement of the liquid, and to so co-ordinate and construct the parts employed as 20 to insure positive relative separation thereof immediately following the displacement stroke of certain of said parts.

With the above and other objects in view, which will appear as the nature of the invention is 25 better understood, the same consists in the improved construction and novel arrangements of parts which will hereinafter be fully described and particularly pointed out in the claims.

In the accompanying drawings has been illustrated a single and preferred form of the invention, it being, however, understood that no limitations are necessarily made to the precise structural details therein exhibited, but that changes, alterations and modifications within the scope of 35 the claims may be resorted to when desired.

In the drawings,

Figure 1 is a vertical section through the means embodying the invention and illustrating same in association with an enclosure for the mechanism to be protected against liquid from an exterior source, the parts being in what may be called the filling stroke of the pistons employed;

Figure 2 is a view similar to Figure 1, showing the parts in the position necessary to effect discharge of the collected liquid;

Figure 3 is a transverse section on line 3—3 of Figure 1;

Figure 4 is a transverse section on line 4—4 of Figure 1;

Figure 5 is a transverse section on line 5—5 of Figure 1;

Figure 6 is a vertical section on line 6—6 of Figure 1.

As in my aforeslated co-pending applications, 55 this invention, in its present embodiment, is

shown for the purpose of illustration associated with a mechanism which includes a crosshead 10 adapted to be reciprocated during operation of the mechanism to impart a corresponding movement to a member 11 in the form of a rod which is secured at one end to the crosshead and operates through a wall of a closed chamber 12 defined by a casing 13 enclosing the mechanism.

The wall of the chamber through which the 10 member 11 extends exteriorly of the chamber for connection to a part (not shown) to be actuated by the member is defined by a plug 14 threaded secured in the casing to close the chamber. A packing gland 15 is associated with 15 the member 11 and includes packing 16 seating in a recess 17 in the plug 14, and a nut 18 threaded into the plug to compress the packing.

Assuming that the casing is disposed in a vertical position in a water or oil well, for example, 20 so that the casing is submerged in the liquid with the member 11 projecting upwardly from the casing into the liquid, a leakage of liquid between the member 11 and the wall of the chamber into the latter will occur during reciprocation 25 of the member, notwithstanding the provision of the packing gland 15.

In order to positively protect the enclosed mechanism against liquid leakage into the chamber 12 as aforeslated, a means is provided for 30 collecting and ejecting the liquid from the casing before the liquid reaches the mechanism below the crosshead 10. In the present instance, this means comprises a receptacle in the form of a deep cylindrical cup 19 secured in any suitable well known manner to the upper end of the cross head 10 and having concentrically arranged equidistantly related cylindrical chambers 20 of which four are shown in the present embodiment. These chambers are formed in the 40 more or less thick bottom wall of the cup and each thereof opens in the direction of the space 21 defined by the annular walls of said cup. The closed ends of these chambers open by way of radial ports 22 to a valve 23 at the lower end 45 of the member 11, said valve having a seat 24 with which a vertically movable ball 25 is adapted to co-act, whereby during one movement of the member 11 the ball will close against its seat and open relatively to the seat on movement 50 of the member 11 in an opposite direction, subject, however, to the operation of means which I will presently describe. The valve 23 co-acts with an axial bore 26 in said member 11, the latter having radial discharge passages 27. 55

Free to slide on the member 11 is a spider 28, a fixed stop collar 29 on the member 11 serving to limit the sliding movement of said spider in one direction. Rods 30 on the respective arms 31 of the spider operate in alined recesses 32 in the bottom of cup 19 and contained in the recesses to bear against the free lower ends of the rods 30 are coil springs 33. These function to hold the hub of the spider against the aforementioned stop collar 29 when the lower end of member 11 is in the position shown in Figure 1. When, however, the lower end of the member is in the position indicated in Figure 2, an annular collar 34 on the under side of plug 14 strikes against the spider and forces same towards the bottom wall of the cup 19 against the action or tension of the springs 33.

Each arm 31 of the spider 28 carries a solid piston 35 having an annular skirt 36, the latter having an annular series of ports 37. These pistons work in the respective chambers 20 and when the parts are in the relative positions shown in Figure 1, the ports 37 open directly into the cup space 21, thus enabling liquid in said space to enter said chambers. But when the parts are in the positions shown in Figure 2, any liquid in said chambers will be displaced into the axial bore 26 of the member 11 in consequence of the structural arrangement of said parts and the valve 23.

In order that the chambers 20 can be timely vented as required, each thereof has a port 38, including a check valve 39 which co-acts with a breather tube 40, the latter extending into the cup space 21 and terminating at the top thereof in a downwardly curved neck 41, thus enabling air to be supplied the chambers as is necessary for a free return of the pistons 35 to intake positions after liquid has been displaced from said chambers.

Having substantially set forth the description of operation of the various parts, a further description of operation is as follows:

Any liquid which finds its way to the cup space 21 will settle in said space and run into the chambers 20 through aforesaid ports 37 in pistons 35. Assuming that such flow is occurring with the parts in the positions shown in Figure 1, it follows that on the upstroke of the cup 19 the hub of the spider 28 will strike the collar 34, thereby advancing the spider in the direction of the bottom of the cup. The solid pistons 35 are forced into the chamber 20 and any liquid contained in the latter will be forced into the axial bore 26 of member 11. In the position shown in Figure 2, the radial ports 27 will be above the plug 14 and liquid rising in the bore 26 will, of course, discharge radially of said member 11 and outside of the casing 13.

It is to be understood that the spider 28 by virtue of the stop collar 29 is limited in its movement to the extent that the lower ends of the pistons 35 can never completely leave their co-acting cylinders 20. This is important in that alinement of the pistons with their chambers is positively insured at all times. By means of the annular series of pistons maximum displacement can be had that will insure complete emptying of the space 21 on each operation of the pistons at the time stated.

The relative term "deep" as employed herein in describing the cup 19 shall relate to the large capacity of the space 21 formed by the annular walls of the cup, which walls serve to cause the spider 28 and its pistons 35 to be wholly contained within said space. It is by means of this con-

struction that the device will accommodate more liquid than was provided for in the form of the inventions disclosed in my copending applications.

What is claimed is:

1. The combination with a casing having a liquid collecting mechanism, including a cup and a reciprocal rod having a valved bore, the cup having an annular series of liquid chambers, of an annular series of ported pistons carried by the rod and movable axially thereof and co-operable with the chambers, the chambers having ports communicating with the bore of the rod; means for moving the pistons in one direction; and means by which motion can be transferred to the pistons to move same in an opposite direction and against the normal action of the first means.

2. The combination, with a casing having a liquid collecting mechanism, including a cup and a reciprocal rod having a valved bore, the cup having an annular series of liquid chambers, of an annular series of ported pistons carried by the rod and movable axially thereof and co-operable with the chambers, the chambers having ports communicating with the bore of the rod; means for moving the pistons in one direction; means for preventing entire withdrawal of the pistons from said chambers; and means by which motion can be transferred to the pistons to move same in an opposite direction and against the normal action of the first means.

3. In a device of the class described, a liquid collecting cup having a bottom formed with an annular series of chambers, the chambers having liquid discharge ports, a spider contained in the chamber and movable relatively to said bottom, and ported pistons mounted for reciprocal movement in the respective chambers and whose ports are adapted to open into the cup above the bottom thereof when the pistons are in one position.

4. In a device of the class described, a liquid collecting cup having a bottom formed with an annular series of chambers, the chambers having liquid discharge ports, a spider contained in the chamber and movable relatively to said bottom, and ported pistons mounted for reciprocal movement in the respective chambers and whose ports are adapted to open into the cup above the bottom thereof when the pistons are in one position, the depth of the cup being in excess of the length of any one of said pistons.

5. In a device of the class described, a liquid collecting cup having a bottom formed with an annular series of chambers, the chambers having liquid discharge ports, a spider contained in the chamber and movable relatively to said bottom, ported pistons mounted for reciprocal movement in the respective chambers and whose ports are adapted to open into the cup above the bottom thereof when the pistons are in one position, and means between the bottom of the cup and the spider for urging the pistons in one direction.

6. In a device of the class described, a cup open at its top and provided with a thick bottom, the latter having a ported chamber, and a solid piston movable in the chamber and provided with a lateral port which is closed by the walls of the chamber when the piston is in one position and which opens into the cup above said bottom when the piston is in another position.

7. In a device of the class described, a cup open at its top and provided with a thick bottom, the latter having a ported chamber, a solid piston movable in the chamber and provided with a lateral port which is closed by the walls of the chamber when the piston is in one position and which opens into the cup above said bottom when the piston is in another position.

ber when the piston is in one position and which opens into the cup above said bottom when the piston is in another position, movable means on which the piston is mounted, and means co-operable with the movable means for moving same.

8. In a device of the class described, a cup open at its top and provided with a thick bottom, the latter having a ported chamber, a solid piston movable in the chamber and provided with a lateral port which is closed by the walls of the chamber when the piston is in one position and which opens into the cup above said bottom when the piston is in another position, movable means on which the piston is mounted, and means co-operable with the movable means for moving same

and including a spring between the bottom of the cup and said movable means.

9. In a device of the class described, a vertically disposed hollow body, open at its upper end and provided with a fluid discharge port and said body having a chamber into which fluid from the body can enter and said chamber being in communication with said port; a reciprocal piston in said chamber, said piston having a perforation through which fluid can enter the chamber from the cup as aforesaid; and a breather tube by means of which the chamber can be supplied with air during movement of the piston in one direction.

EDWARD C. EKSTROMER. 15
